Patented Nov. 26, 1974

233,790

HOUSING FOR A CLOCK RADIO

John T. Houlihan, Fayetteville, N.Y., assignor to
General Electric Company

Filed May 11, 1973, Ser. No. 359,547

Term of patent 14 years

Int. Cl. D14—03

U.S. Cl. D56—4 B

FIG.1

FIG.2

FIG.3

FIG.4

FIG.5

FIG.6

FIG. 1 is a front elevational view of a housing for a clock radio showing my new design;

FIG. 2 is a top plan view;

FIG. 3 is a right side elevational view;

FIG. 4 is left side elevational view;

FIG. 5 is a rear elevational view; and

FIG. 6 is a bottom plan view.

I claim:

The ornamental design for a housing for a clock radio, as shown.
